E. COOKINGHAM,
WINDOW SAFETY CATCH.
APPLICATION FILED APR. 24, 1920.

1,366,245.

Patented Jan. 18, 1921.

E. *Cookingham*

INVENTOR.

BY

John Randolph Jr. ATTORNEY.

UNITED STATES PATENT OFFICE.

ELMYNA COOKINGHAM, OF SAGINAW, MICHIGAN.

WINDOW SAFETY-CATCH.

1,366,245.

Specification of Letters Patent. Patented Jan. 18, 1921.

Application filed April 24, 1920. Serial No. 376,326.

To all whom it may concern:

Be it known that I, ELMYNA COOKINGHAM, a citizen of the United States, residing at Saginaw, in the county of Saginaw and State of Michigan, have invented certain new and useful Improvements in Window Safety-Catches; and I do hereby declare the following to be a full, clear, and exact description of the invention, such as will enable others skilled in the art to which it appertains to make and use the same.

This invention relates to new and useful improvements in window catches and has for its primary object the provision of means which will automatically lock a window sash at its various positions in a window frame, when said means is manually released, thereby insuring the window sash being locked against movement at all times.

Another object of this invention is the provision of a window catch of the above stated character, which shall be simple, durable and efficient, and which may be manufactured and sold at a comparatively low cost.

With these and other objects in view as will become more apparent as the description proceeds, the invention consists in certain novel features of construction, combination, and arrangement of parts as will be hereinafter more fully described and claimed.

For a complete understanding of my invention, reference is to be had to the following description and accompanying drawing, in which:

Figure 1 is a front elevation of a window frame and sash, partly in section, illustrating a catch applied to the window sash and constructed in accordance with my invention.

Fig. 2 is a side elevation partly in section of the catch.

Fig. 3 is a plan view illustrating the openings in the closure plate to permit the locking feet to extend therethrough.

Referring in detail to the drawing, the numeral 1 indicates a window frame in which is slidably mounted a window sash 2. The window sash 2 is provided with a recess 3 that opens outwardly through one edge thereof to receive the catch 4 that is adapted to engage a rack plate 5 secured to the window frame 1 whereby the window

sash can be locked at various positions within the window frame.

A closure plate 6 is secured to the window sash 2 by fasteners 7 so as to close the recess 3 and has formed thereon inwardly extending lugs 8 to form feet for a flexible member or spring, 9. The flexible member or spring 9 intermediate its ends is provided with an opening to slidably receive a stud 10 secured to the plate 6 and on which is mounted a spring 11 of the expandable type. Blocks or feet 12 are secured to the ends of the member or spring 9 and extend through slots 13 formed in the closure plate 6 and have their outer faces serrated to engage the rack plate 5 for holding the window sash 2 at various positions, along the window frame. The feet 12 are normally urged into engagement with the rack plate 5 by the spring 11.

A frame 14 is located in the recess 3 and slidably receives a tubular member 15 which slidably receives the inner end of the stem or stud 10 and bears against the spring or flexible member 9. The tubular member 15 extends through the window sash and is provided with a finger grip 16 so that on pressing the finger grip 16, the spring or flexible member 9 will be flexed causing the feet 12 to disengage the rack plate 5 and permit the window sash 2 to move freely upwardly and downwardly in the window frame. As soon as pressure is released from the finger grip 16, the spring 11 forces the feet 12 into engagement with the rack plate 5 again locking the window sash automatically. A collar 17 is secured to the tubular member 15 and abuts the frame 14 for limiting the outward movement of said tubular member 15 and also for limiting the flexing action of the spring or flexible member 9 in one direction.

The frame 14 consists of a body 18 which is provided with end walls 19 that are offset as illustrated at 20 to form chambers 21 that permit or receive the feet 12 as they move inwardly to disengage from the rack plate. The end walls 19 where they are offset from seats 22 that coöperate with the seats 8 in supporting the spring or flexible member 9. The flexible member or spring 9 is free to slide between the seats 22 and 8 during the operation of the catch. The body 18 is secured to the closure plate 6 by rivets 23 so that the entire catch can

be assembled and then placed into the recess 3 of the window sash and secured therein by the fastening element 7 passing through the closure plate and threaded into 5 the window sash. The openings in the closure plate 6 that receive the fastening 7 are of the countersunk type so that the heads of the fasteners are embedded or disposed in a plane inwardly of the outer face 10 of said closure plate.

While I have shown and described the preferred embodiment of my invention, it will be understood that minor changes in construction, combination, and arrangement of parts may be made without departing from the spirit and scope of the invention as claimed.

Having thus described my invention, what I claim is:

20 1. A window catch comprising a frame carried by a sash, a flexible member movably mounted in said frame, feet carried by said flexible member and adapted to engage a stationary rack plate, means engaging the 25 flexible member to flex the same in one direction to engage the feet with the rack plate, and manual operating means engaging the flexible member to flex the same in an opposite direction to disengage the feet 30 from the rack plate.

2. A window catch comprising a frame, seats formed in said frame, a flexible member slidable between said seats, locking elements carried by said flexible member, tension means flexing said flexible member in one direction to engage the locking elements 35

with a stationary rack plate, and a push button slidable in said frame and engaging the flexible member to flex the same in an opposite direction to disengage the locking elements from the rack plate.

3. A window catch comprising a closure plate secured to a sash and having openings, seats formed on said plate, a frame secured to said plate, seats carried by said frame 45 and arranged adjacent the first named seats and defining offset portions to said frame to provide chambers, a flexible member slidable between said seats and having its ends disposed in said chambers, locking elements 50 carried by the ends of the flexible member and movable through the openings in the closure plate to engage a rack plate, a stud carried by the closure plate and extending through the flexible member, a 55 spring on said stud and bearing against the flexible member to flex the same in one direction to engage the locking elements with the rack plate, a sleeve slidable in the sash and frame and receiving the stud and 60 bearing against the flexible member, a finger grip secured to said sleeve to permit a person to flex the member in an opposite direction for moving the locking elements away from the rack plate and into said 65 chambers.

In testimony whereof I affix my signature in presence of two witnesses.

ELMYNA COOKINGHAM.
